UNITED STATES PATENT OFFICE.

HAROLD J. GOSS, OF NASHUA, NEW HAMPSHIRE, ASSIGNOR, BY MESNE ASSIGNMENTS, TO THE LAKE ERIE TRUST COMPANY, OF CLEVELAND, OHIO, A CORPORATION OF OHIO.

MACHINE FOR MAKING SET-UP BOXES.

Application filed June 26, 1923. Serial No. 647,849.

To all whom it may concern:

Be it known that I, HAROLD J. Goss, a citizen of the United States, and resident of Nashua, in the county of Hillsborough 5 and State of New Hampshire, have invented certain new and useful Improvements in Machines for Making Set-Up Boxes, of which the following is a specification.

This invention relates to the manufacture 10 of paperboard boxes and has particular reference to machines for making rectangular boxes in set up form, ready to have goods placed therein. The boxes of this type are referred to as wall boxes for the reason 15 that they present upright side portions which serve as walls to retain goods.

The object of the invention is to provide an improved machine which is rapid and 20 automatic in operation, the blanks being fed singly and successively to the machine, folded therein, and delivered therefrom in 25 firmly set up condition.

With this object in view the invention consists in the construction and combination 25 of parts substantially as hereinafter described and claimed.

Of the accompanying drawings:

Figure 1 is a perspective view of the machine, omitting details of some parts to 30 avoid confusion, said omitted details being illustrated in other figures.

Figure 1^a is a detail perspective view of the blank pushing finger at the end of one 35 of the sliding rods.

Figure 2 represents a longitudinal section of the machine, omitting some portions thereof and some portions being partly broken out.

Figure 3 is a detail plan view of the 40 mechanism for squaring up the blanks after they leave the feeder, to ensure straight travel through the gluing and folding mechanism, the middle portion of said mechanism being broken out to reduce 45 width of the figure.

Figure 4 is a detail perspective view of the plunger mechanism which effects complete folding of the blanks to set up condition.

Figure 5 represents a section on line 5—5 50 of Figure 2, on a larger scale.

Figure 6 represents a section on line 6—6 55 of Figure 4 on a larger scale.

Figures 7, 8, 9, 10, 11, 12 and 13 are

perspective views illustrating successive operations on a blank passing through the machine.

Similar reference characters indicate similar parts in all of the views, numerals being employed for the machine, and letters for the blanks being operated upon.

A suitable frame 12 is provided with brackets 13, the latter having bearings for the shaft 14 of feed wheels 15. The blanks, which are supported by a table not necessary to illustrate, are drawn successively over retarders 16 (Figs. 1 and 2) adjustably mounted on a tie rod 17, and are fed over rolls 18 carried by arms 19 the hubs 20 of which are pivotally mounted on the tie 70 rod 17. Said hubs have tail pieces 21 to which springs 22 are connected to cause the rolls 18 to bear yieldingly against the combining feed wheels 15. This construction enables each roll 18 to yield relatively to the 75 combining wheel 15 above it independently of the other roll 18, to aid in forwarding the blanks without their turning askew.

Extending longitudinally of the machine (Figs. 1, 2 and 5) are two parallel bars 23 mounted on tie rods 24 so as to be laterally adjusted thereon. Idly mounted in line with the front end of each bar 23 is a sprocket 25. In line with the rear ends of said bars are sprockets 26, carried by a 80 driven shaft 27. Mounted on the four sprockets and riding along the upper edges of the bars 23 are two chains 28 having spaced pins 29 to engage the rear edges of the blanks as hereinafter described. Each chain is laterally guided by ribs 30 of the bars 23 (Fig. 5). Strips 31, the upper edges of which are substantially flush with the tops of the ribs 30, are located between the bars 23, being supported by posts 32 mounted on tie rod 33 and on one of the tie rods 24 and secured in proper lateral position thereon by set screws 34. A pair of upper guide strips 35 are carried by rods 36 which project inward from brackets 37 supported as herein- 90 after described.

To effect the application of glue to selected portions of each blank as hereinafter described, I provide a pair of glue boxes 39 each having a roll 40 for a film of glue. 105 A guide or pressure roll 41 is yieldingly mounted above each roll 40.

The machine constructed as illustrated is

2
designed to operate on blanks each of which, when flat, (Fig. 7) consists of a middle portion *a* to form the bottom of a box, end wall sections *b* the outer edges of which are straight, and side wall sections *c* having flaps *d* which are of the same length substantially as the sections *b* but with ogee shaped tips as shown by Figure 7. The machine is not, however, limited in its use
10 to folding blanks of this specific shape.

In order that each blank may be centralized as it leaves the feed wheels, and preferably just after its rear edge is engaged by a pair of chain pins 29 to push it along, 15 I employ devices which, for convenience, I refer to as joggers. As shown by Figures 1, 3 and 7, two parallel rods 42, 43, are mounted to have a short sliding movement in the frame of the machine, and they carry 20 two upright wall members 44 each having a horizontal shelf 45 one end of which, onto which a blank rides, is curved downwardly. Each device 44, 45, is carried by the upper edge of a pin 46. One of these pins 46 rises from a block 47 which is adjustably clamped to the rod 42 and slides on rod 43, and the other pin 46 rises from a block 48 which is adjustably clamped to rod 43 and slides on rod 42, so that as the 25 rods slide in opposite directions the joggers move toward and apart from each other, the blocks being so adjusted relatively to each other that one or the other will push a blank to central position. As will now 30 be described, the two rods 42, 43, are automatically actuated to cause the distance between the two jogger walls 44, when reaching their limit of movement toward each other, to just equal the width of a 35 blank. And the timing of operation is such as to cause the joggers to act against the straight outer edges of the sections *b* of the blank. The rods 42, 43, are normally held 40 with the joggers at their outer or spread 45 limits of movement by a spring 49 (Fig. 3) under compression between two abutments 50 each of which is secured to one of the rods. I shall now describe the means for 55 shifting the rods to cause the joggers to act as indicated in Figure 7. Adjustably secured to each rod 42, 43, is a roll 51 (Figs. 1 and 3). To spread the two rolls 51 apart at the proper times so as to slide the rods in opposition to the spring 49, I 60 employ a wedge 52 carried by a lever 53 pivoted at 54 and having a roll 55 actuated by a cam 56 carried by the shaft 14, a suitable spring 57 being employed to effect return movement of the lever. The timing 65 is such that the wedge causes the two joggers 44 to approach each other each time that the feed rolls have advanced a blank to the position indicated by Figure 7 and a pair of chain pins 29 have engaged its rear edge. During such advance, the blank travels in

the direction of the arrows in Figures 3 and 7, its marginal portions riding onto and over the little shelves 45 of the joggers.

After the jogging or squaring up operation, the portions *b* are broken down in order 70 that only the flaps *d*, and the under surfaces thereof, will receive glue from the rolls 40. To break the portions *b* down, I employ arms 58 carried by a shaft 59 having a sprocket 60 (Fig. 1) connected by chain 75 61 with a sprocket 62 carried by the shaft 14. These connections are such as to effect a timing that will, just after the blank has advanced from the position shown by Figure 7 to the position shown by Figure 8, cause 80 the rotary depressing arms 58 to break the sections *b* on their crease lines so that as the blank continues to advance, the sections *b* will be deflected below and inside of a pair of guide fingers 63 supported by 85 a universal joint connection 64 (Fig. 1) with a suitable portion of the machine such as a rod 65. The rod 65 extending from each glue box supports, by a universal joint connection, a finger 66 the far end of which 90 leads onto the top of the glue box. The fingers 63, 66, are adjusted to such inclinations that, as the blank is pushed along, the two sections *b* which have been depressed by the rotary arms 58, are guided 95 down to substantially vertical positions inside the glue boxes and against the surfaces of the inner walls of the two glue boxes 39 and consequently receive no glue, while all 100 four of the flaps *d*, *d*, since they are not acted upon by the rotary depressing arms, pass above the fingers 63 and from them onto the fingers 66, and from the latter onto the glue boxes and over the glue rolls 40 as indicated in Figure 9. To enable the 105 downwardly turned sections *b* to pass along, the glue boxes are slightly spaced away from the outer surfaces of the bars 23 as indicated in Figure 5. The fingers 110 63, 66, are omitted in Figure 9, but their position relatively to the glue boxes is clearly shown in Figure 1.

After the blank has been advanced by the chain lugs or pins far enough so that the under surfaces of all four flaps *d*, *d* have received glue from the rolls 40, its movement is accelerated by mechanism which not only separates its rear edge from said lugs so that the said lugs will not tear notches in said edge when the lugs pass 115 down around the sprockets 26, but also pushes the blank to the position where it is to be folded. Said mechanism comprises a pair of rods 67 (Figs. 1, 1^a, 3, 5 and 10) mounted to slide in bearing blocks 68 secured to the bars 23 and actuated as presently described. Each rod 67 at its front end (Fig. 1^a) has a block 69 in which is pivoted, at 70, a finger 71 having a notched 120 front end. A spring 72 normally holds the 125

finger tilted slightly upward with its notch in the plane of a blank. When the two rods move back, their two fingers will readily swing down so as to freely pass back under a blank, and after so passing back, the fingers will spring up so their notches will be in position to engage the rear edge of the blank under which they have just retreated, and to push that blank forward 10 when the rods slide forward (Fig. 10).

The mechanism for reciprocating the push rods 67 comprises a rock shaft 73 (Figs. 1 and 2) having two long arms 74 connected at their upper ends by a small cross rod 75. Each push rod has a block 76 secured to it, a pin 77 extending downwardly from it into a socket 78 mounted on the cross rod 75, whereby rocking movements of the shaft 73 transmit sliding movements to the push rods through the arms 74 and the pins 77. The rock shaft is actuated by a cam 79 carried by a shaft 80, and a link 81 having a roll 82 engaged by the cam and connected to a short arm 83 of the rock shaft 73, a suitable spring being employed to hold the roll 82 in contact with the cam.

The throw of the arms 74 is such that when they move to the position indicated in Figure 2, the notched fingers 71 of the slide rods push the the blank to position to be folded, the blank being arrested in that position by a pair of stops 84 adjustably mounted in blocks 85 which, in turn, are laterally adjustable on a tie rod 86. Each stop 84 carries a ledge 87 having a bevelled tip for the front edge of the blank to ride onto.

As the blank is pushed to position against the stops, it rides under a pair of spring fingers 88 carried by a cross rod 89 mounted on the upper guide strips 85 (Figs. 1, 2 and 10). These fingers are so mounted that their free ends are above the ends of the guide strips 85 and bear lightly on the blank to prevent it from rebounding from the stops 84 (see Fig. 2). A substantially rigid inclined finger 90 is also mounted on the cross rod 89 in position to prevent the mid-width portion of the blank from curving up or "bulging" due to the sections *b b* being held down as the blank is pushed to position across the plungers presently described. To hold said sections *b b* down as just mentioned, a guide rod 91 is employed on each side extending as indicated in Figs. 1 and 10, and connected by an adjustable clamp 92 with a rod 93 projecting outwardly from the bar 23, said rod 93 serving also to support the bracket 37.

When a blank has been advanced to the position shown in Figure 2, it is just above upwardly movable plunger mechanism and below a vertical chamber through which the blank is moved while being folded. To support the latter, two tie rods 94 (Figs.

1 and 2) extend across from side to side of the frame of the machine. Front and rear wall plates 95, having outwardly curved lower ends, are rigidly carried by lugs 96 which are slotted and have screws extending into blocks 97 which are adjustably mounted on the tie rods 94. The slotted lugs 96 and the screws enable the plates 95 to be adjusted to suit different widths of boxes to be made, and the adjustable mounting of the blocks 97 on the tie rods provides for different lengths of boxes. Four of the plates 95 are provided with vertical slots through which yieldingly mounted members 98 project to serve as strippers as hereinafter explained.

At each end of the box-forming chamber is a pressure plate 99 having an inwardly projecting ledge 100 at its upper edge. Each plate 99 is carried by a slide 101 mounted on the two tie rods 94 and having an anti-friction roll 102 against which a cam 103, carried by a shaft 104, acts to move the slide 101 and pressure plate 99 inward. There is a shaft 104 for each slide and pressure plate, and an anti-friction roll 105 is supported by the frame behind each cam to sustain the pressure when the two plates 99 are acting on the ends of the box as hereinafter described.

Each shaft 104 has a sprocket 106 (Fig. 1) driven by a chain 107 from a sprocket 108 carried by the shaft 80. Suitable springs 109 effect outward movement of the slides 101 after the cams have performed their functions.

The lower ends of the corner plates 95 have outwardly flaring guides 110 to facilitate the folding of the flaps *d* as illustrated by Figure 11, when the compound plungers which will now be described rise and lift the blank.

To guide the plunger mechanism vertically (Figs. 2 and 4) bearing blocks 111 are mounted on tie rods 112. A plunger 113 having a recessed upper face with bevelled end edges 114 (see also Figure 13), has a channelled stem 115 mounted to slide in the blocks 111. A flat-surfaced plunger 116 has its stem 117 mounted to slide within the channelled stem 115.

A rock shaft 118 (Fig. 2) has two arms 119 (Fig. 4) connected by links 120 to opposite sides of the channelled stem 115 and has another arm 121 carrying a roll 122 which is acted upon by a cam 123 carried by shaft 80. A rock shaft 124 has an arm 125 connected by a link 126 to the stem 117 and has another arm 127 carrying a roll 128 which is acted upon by a cam 129 also carried by shaft 80. Suitable springs such as indicated in Figure 2 may be employed to ensure prompt return movements of the rock shaft arms. The cams 123, 129, are omitted from Figure 1 because they are at

the far end of shaft 80 and to include them in that figure would confuse other parts.

The shaft 80 has a gear 130 (Fig. 2) meshing with a pinion 131 carried by a 5 stud shaft 132, said shaft having a gear 133 driven by a pinion 134 carried by the main shaft 135 of the machine.

Some of the driving connections which are shown in Figure 1 are not described be- 10 cause they are not important and may be different from the illustration.

In operation, each blank fed by the combing wheels 15 arrives on the ribs 30 of the bars 23 (Fig. 7), the timing of operation 15 of the combing wheels and the chains 28 being such that the rear edge of the blank arrives somewhat in advance of a pair of chain pins 29. The friction between the blank and the ribs 30 retards the blank un- 20 til said pins engage its rear edge. Immediately after such engagement and the con- sequent pushing of the blank along, the joggers 44 approach each other and centralize the blank. As the blank then proceeds, its 25 end wall sections *b b* are broken down by the rotary depressers 58 (Fig. 8) and pass under the fingers 63 and then along against the inner walls of the glue boxes 39 (Fig. 9). The flaps *d d* however are not deflected 30 down and they pass over the glue rolls, and receive glue on their under surfaces. During this portion of the forward movement 35 of the blank the sliding push rods 67 are re- treating until their notched fingers 71 can spring up behind the rear edge of the blank, and then the rods move forward and acceler- 40 ate the advance of the blank pushing it under the spring fingers 88 (Fig. 10) and against the stops 84 (Fig. 2). Then the plunger 116 rises, immediately followed by 45 the plunger 113, lifting the blank in such manner that, while the sections *b b* are held down and partly in by the bent guides 91 (Fig. 11), the sections *c c* are swung toward 50 each other by riding against the inner sur- faces of the outwardly curved lower ends of the plates 95. At the same time the flaps *d d* are bent on their crease lines by the 55 guides 110 so that as the blank continues to rise, the said flaps, having cleared the guides 91 (Fig. 12) approach each other edge to edge outside of the sections *b b*, ready to have their inner glue-carrying surfaces 60 pressed against said sections *b b*, when the blank is raised still higher entirely above the upper edges of the guides 110 in Fig. 12.

As shown by Figures 4, 12 and 13, there is a ledge 136 projecting from each end of the plunger 113 at the bottom thereof. 65 When the blank is in about the position shown in Figure 12, its flaps *d d* are folded in above the ledges 136. At this time the plunger 113 has not caught up with the plunger 116 and therefore there is room for the flaps to be so folded. As the blank is

moved up to the position shown in Figure 13, between the end pressers 99 which now move in, the plunger ledges 136 push the flaps *d d* into alignment and cooperate with the ledges 100 in causing the now top and bottom edges of the flaps to be flush with the top and bottom of the sections *b b*. Then the final closing of the pressure plates 99 toward each other effects complete forma- 75 tion of the box.

After the pressure plates move apart, the plunger 116 is moved still higher to remove the box from the plunger 113 and carry it above the strippers 98 where it will remain during the downward movement of the 80 plungers. To effect this movement of the plunger 116, its actuating cam 129 has one portion considerably higher than the other as indicated in Figure 2, which higher portion effects the last mentioned discharging 85 movement of said plunger 116.

The completed box is caught by the strippers 98 and rests thereon until the completion of another box, and the lifting thereof, effects its displacement by pushing it up 90 clear of the plates 95. To cause each box, as it emerges from the top of the chamber between the plates 95, to tilt in a predetermined direction into any suitable delivery 95 chute, I provide a pair of curved spring deflectors 137 (Figs. 1 and 2) mounted on two of the slotted plates 96.

To avoid any possibility of a blank shifting laterally or turning askew as it is pushed to position to be acted upon by the plungers, I provide a pair of side guides 138 (Figs. 1 and 2) adjustably mounted at one end on the tie rod 86 and having their other ends somewhat flared to admit the 105 blank between them.

Having now described my invention, I claim:

1. A machine for making wall boxes from blanks having corner flaps and intermediate foldable sections, comprising means for causing the blanks to travel, means for deflecting said intermediate sections while traveling, means for applying glue to the corner flaps while they extend outwardly, means for folding the blanks with said flaps and sections in overlapping relationship, means for holding the folded blanks temporarily in stationary position, and pressers movable toward the folded blanks while the latter are stationary.

2. A machine for making wall boxes from blanks having corner flaps and intermediate foldable sections, comprising means for causing the blanks to travel, means for breaking said intermediate sections downwardly while traveling, means for applying glue to the corner flaps while they extend outwardly, and means for folding the blanks with said flaps and section in over- 125 130 135

3. In a box-making machine having means for causing blanks to travel singly and successively toward folding instrumentalities, a pair of upright joggers spaced to permit the blanks to pass between them, and means for causing the joggers to intermittently approach each other, said joggers having inwardly projecting shelves over which edge portions of the blanks ride. 65
- 10 4. In a box-making machine having means for causing blanks to travel singly and successively toward folding instrumentalities, a pair of parallel rods mounted to slide cross-wise of the machine and each having an upright member in position to act on an edge portion of each blank, and means for causing said rods to simultaneously slide in opposite directions. 70
- 15 5. In a box-making machine having means for causing blanks to travel singly and successively toward folding instrumentalities, a pair of parallel rods mounted to slide cross-wise of the machine and each having an upright member in position to act on an edge portion of each blank, each of said rods having a roll, a spring for normally holding the rods, with the peripheries of said rolls in proximity, a lever having a wedge to enter between said rolls, and means for actuating said lever. 80
- 20 6. A machine for making wall boxes from blanks having corner flaps and intermediate foldable sections, comprising means for causing the blanks to travel, a pair of gluers, means for directing the corner flaps over the gluers, means for breaking the intermediate sections down to enable them to pass inside the inner walls of the gluers, and means for folding the blanks with their corner flaps outside of the said intermediate sections. 90
- 25 7. A machine for making wall boxes from blanks having corner flaps and intermediate foldable sections, comprising means for causing the blanks to travel, a pair of gluers, means for directing the corner flaps over the gluers, a pair of rotary depressers in position to engage the intermediate sections of the blanks and break them down, and means for folding the blanks with their corner flaps outermost. 95
- 30 8. A machine for making wall boxes from blanks having corner flaps and intermediate foldable sections, comprising means for causing the blanks to travel, a pair of gluers, rotary arms for breaking said intermediate sections down, adjustable fingers in position to direct the corner flaps over the gluers and to retain the intermediate sections deflected downwardly, and means for folding the blanks with their corner flaps outermost. 105
- 35 9. A machine of the character described having folding instrumentalities, a guide strips and means for causing blanks to move along said strips and deliver them to position for folding, and an inclined finger between the delivery ends of said strips to prevent upward flexing of mid-width portions of the blanks, as they approach folding position. 110
- 40 10. In a machine for making wall boxes, a forming chamber comprising a pair of parallel rods having blocks mounted thereon and wall plates adjustably mounted on the blocks to vary the size of the chamber, a plunger movable to and from the chamber, means for supplying blanks singly to position to be pushed into the chamber by the plunger, and end pressers movable toward and from the space between said wall plates. 120
- 45 11. In a machine for making wall boxes, a pair of parallel rods, wall plates supported by said rods, a pair of slides also mounted on said rods and having pressure plates movable toward and from the space between the wall plates, a plunger movable to push a blank into said space, and means for supplying blanks singly to position to be acted upon by the plunger. 130
- 50 12. In a machine of the character described, a duplex plunger one member of which is formed to engage the central portion of a blank and the other member has end faces, a forming chamber into which a blank is pushed for folding, and presser plates movable toward and from said plunger end faces. 140
- 55 13. In a machine of the character described, a duplex plunger one member of which is formed to engage the central portion of a blank and the other member has end faces, a forming chamber into which a blank is pushed for folding, presser plates movable toward and from said plunger end faces, said presser plates having inwardly projecting ledges at their tops, and the plunger member having the end faces being provided with outwardly projecting ledges to cooperate with those carried by the presser plates in ensuring correct folding of flap portions of the blank. 150
- 60 14. In a machine of the character described, a duplex plunger one member of which is formed to engage the central portion of a blank and the other member has end faces, a forming chamber into which a blank is pushed for folding, presser plates movable toward and from said plunger end faces, and means for imparting a longer stroke to the first-mentioned plunger member than to the member having the end faces. 160

In testimony whereof I have affixed my signature.

HAROLD J. GOSS.
